United States Patent Office

Des. 194,366
Patented Jan. 8, 1963

194,366

LINK FOR AN EXPANSIBLE BRACELET OR SIMILAR ARTICLE

Nathan Goodman, Forest Hills, N.Y., assignor to Baldwin
Bracelet Corporation, New York, N.Y., a corporation
of New York

Filed May 10, 1962, Ser. No. 70,136

Term of patent 7 years

(Cl. D45—4)

FIG. 1.

FIG. 2.

FIG. 4.

FIG. 1 is a top plan view of a link for an expandable bracelet showing my new design;

FIG. 2 is a side elevational view thereof;

FIG. 3 is an end elevational view thereof; and

FIG. 4 is an enlarged perspective view thereof.

I claim:

The ornamental design for a link for an expandable bracelet or similar article, substantially as shown.
